UNITED STATES PATENT OFFICE

JAKOB BERTSCHMANN, OF SAMADEN, SWITZERLAND, ASSIGNOR TO THE FIRM RAUSCHER & STÖCKLIN, OF SISSACH, SWITZERLAND

METHOD OF INCREASING THE RAIL GRIP OF RAILWAY VEHICLES

Application filed December 21, 1928, Serial No. 327,718, and in Germany May 5, 1928.

With sand-sprinkling devices as at present employed the sand is carried in special boxes on the vehicle and is passed from these by air pressure or gravity through tubular passages onto the rails. These sand-sprinkling devices are often unreliable because the sand in the boxes and tubular passages easily becomes wet, binds together and cannot be delivered through the tubular passages even under considerable air pressure.

Now the novel feature of the present invention is that the sand is provided at the position of use or in the immediate neighbourhood of same and for example in the form of an artificial sand-stone carried by the travelling vehicle and which will yield sand when pressed onto the rail. Alternatively sand may be scraped off the artificial stone by means of a rotating friction member, said sand passing onto the rail directly in front of the driving wheels, or the stone may be arranged to abut against the periphery of a driving wheel.

The advantage of employing the rail for rubbing off the sand from the artificial stone is that the rail is freed from adhering oil, grease, or dirt which generally causes slipping of the driving wheels. When a rotating friction member is employed for scraping off the sand it is possible to apply as much sand as is required to the rails even on long journeys.

The artificial stone may be manufactured for example by causing suitable sand (quartz sand) to bind or set with the help of a binding means such as cement. The granularity of the resulting artificial sand-stone should be such that said sand-stone will yield sand freely, not becoming dirty and smooth by taking up oil and grease from the rail but remaining rough.

Two constructional examples of the apparatus are shown in the accompanying drawing.

In the drawing:—

Fig. 1 shows in vertical section a device for applying a block of sand-stone directly to the rail.

Fig. 2 is a plan of the device shown in Fig. 1.

Fig. 3 shows on a smaller scale, two of the

devices according to Figs. 1 and 2 mounted on the under-carriage of a railway vehicle.

Fig. 4 shows by way of example only the electric circuits for the actuation of a plurality of electromagnets. The electromagnets may however be otherwise actuated as required.

Fig. 5 shows an alternative construction in which a rotating friction member is employed.

Fig. 6 shows the device applied to an engine.

In the constructional example according to Figs. 1-4 an artificial stone 1 is removably mounted in a holder 2. A rod 3 with two sets of teeth is secured to the holder 2, said rod being vertically guided in a guide 10. The guide or housing 10 is secured to the under-carriage 11 of the driving vehicle. In each toothed portion (rack) of the rod 3 there engages a toothed wheel 4. The toothed wheels 4 are secured to shafts 12, 13 rotatably mounted in the housing 10. The spiral springs are arranged on the shaft 12, said springs being secured at one end to the corresponding toothed wheel 4 and at the other end to the housing 10. Arranged on the shaft 13 is a spring 7 secured at one end to the housing 10 and at the other end to the corresponding toothed wheel 4. Springs 6, 7 tend to rotate the wheels 4, 4 to push the rod 3 downwardly and hence to press the stone 1 against the rail 14.

A ratchet wheel 15 is secured to the shaft 13 and is engaged by one arm of a two armed pawl 9. A pin 16 is provided on the other arm of the pawl 9, said pin projecting into an electromagnet 8. When the electromagnet is energized a bolt 17 therein strikes against the pin 16 and by this means the pawl 9 is withdrawn from the ratchet wheel 15 allowing the springs 6, 7 to rotate the wheels 4, and to press the stone onto the rail 14. The stone 1, consisting of quartz sand bound or set with cement is removably mounted in the holder 2. It is maintained in position by means of projections 18 engaging grooves in the stone.

When the electromagnet 8 is excited the stone 1 is pressed onto the rail by the springs 6, 7 and cleans said rail, adhering oil and dirt

being removed from the rail so that the driving wheels will then have sufficient grip and slipping of same will be avoided. As soon as the electromagnet 8 is cut out of circuit the 5 pawl 9 again engages the ratchet wheel 15. Owing to the up and down movement of the under-carriage of the vehicle relatively to the rails when the vehicle is in movement, the stone 1 with the holder 2 is spaced above 10 the rail so that friction with the rail cannot occur when the stone is in the withdrawn position.

In order that the pressure of application of the stone to the rail may be sufficiently 15 great even when the stone is considerably worn a spring 20 is advantageously arranged between cranks 21, 22 on the shafts 12, 13. The spring 20 grips onto eccentric pins 24. The tension of the springs 6, 7 is such that 20 when a new stone is inserted in the holder 9 the necessary pressure transmitted to the stone by the springs 6, 7 is exceeded. The spring 20 initially opposes the pressure of the springs 6, 7 to reduce the pressure to the 25 correct value. When however the stone 1 has become worn and in consequence the springs 6, 7 have lost their initial tension, the spring 20 comes into operation, by virtue of the change in position of the cranks, to assist the 30 action of the springs 6, 7.

The stone 1 may alternatively slide along the periphery of the driving wheel, or, as diagrammatically shown in Fig. 5, a rough disc 35 26 could be provided, against which the stone 1 is pressed. The disc 26 would be rotated and would remove sand from the stone 1, said sand falling between the periphery of the wheel and the rail 14. The disc 26 could be driven by rolling on the rail 14. A special 40 drive could however be provided for the disc 26 from the driving wheel of the vehicle or from a small electromotor.

For each of the driving wheels of an engine two devices are arranged in such a manner that one of the devices is ready for use 45 in what ever direction the engine runs. To bring the device in operation the switch 30, or 31 is closed, thus the circuit through all the electromagnets 8 is closed simultaneously and the stones released.

What I wish to secure by U. S. Letters Patent, is:—

1. A method of increasing rail grip by sanding the rails of railway vehicles, consisting in pressing an artificial sand-stone in front of the driving wheel of the vehicle, on to the rail with such force that sand is scraped off said artificial sand-stone onto the rail.

2. A device for carrying into effect the method defined in claim 1, comprising in combination an artificial sand-stone, a holder for said sand-stone, means adapted to press said sand-stone on to the rail, retaining means adapted to hold said sand-stone out of

engagement with the rail against the action of the said pressing means and means to release the last said retaining means.

3. A device comprising in combination a stand-stone, a holder for said sand-stone, a rack fixed to said holder, at least one pinion engaging said rack, springs acting on said wheel to press the holder downward, a retaining member adapted to lock the holder against the action of said springs, electromagnetic means to release said holder. 75

4. A device comprising in combination a sand-stone, a holder for said sand-stone, a rack fixed to said holder, at least one pinion engaging said rack, springs acting on said wheel to press the holder downward, a pawl engaging a member standing under the pressure of said springs, an electromagnetic device to withdraw said pawl. 80

5. A device comprising in combination a sand-stone, a holder for said sand-stone, a double rack fixed to said holder, two toothed gears each engaging one of the racks, two levers each being fixed to a shaft of one of said gears, a spring interconnecting the said two levers, additional springs adapted to press the sand-stone downwards, a locking element adapted to hold the sand-stone against the action of said springs and electromagnetic means to release the sand-stone. 90

In testimony whereof I affix my signature.

JAKOB BERTSCHMANN.
